UNITED STATES PATENT OFFICE.

JOHN W. PITTS, OF BERKELEY, CALIFORNIA.

TOBACCO-PIPE CLEANER.

Application filed May 4, 1925. Serial No. 27,912.

The present invention relates to a method and apparatus for cleaning tobacco pipes.

The general object of the invention is to provide for cleaning the bowl and stem of a tobacco pipe by circulating a current of heated air therethrough.

The above and other objects are accomplished by instrumentalities pointed out in the following specification, in so far as they go beyond the shoulder 12. The boss operates to

10. The invention is clearly defined in the claims, the deflector 13 against upward displacement. The skeleton bracket 17 is

A satisfactory embodiment of the invention is illustrated in the accompanying drawings forming part of the specification and in which the bit is formed of resilient metal and the arms thereof curved outwardly and downwardly 70 and then inwardly so that the free ends and in which the bit is formed of resilient metal and the arms thereof curved outwardly and downwardly 70 and then inwardly so that the free ends 19 of

Figure 1 is a view partly in side elevation of the deflector. The transverse area of the and vertical section showing the operation bracket is such as to permit the same to be of cleaning the pipe in accordance with the readily inserted into the bowl of a pipe;

Figure 2 is a horizontal cross section of the same will contract laterally more or less in the line 2-2 of Figure 1, and in accordance with the diameter of the bowl.

Figure 3 is a view similar to Figure 2, on so that the pipe will be frictionally held by the line 3-3 of Figure 1.

The pipe cleaner of the present invention 25 comprises a base *a* which is by preference formed of metal and of a fanciful design. The base is adapted to stand upright upon a table or other support and may have a plurality of knobs 5 on its lower edge for holding the latter in spaced relation to the support and adding to its attractiveness. 30

hollow intermediate section constituting a chamber 20 in which is disposed an electric heating element of any well known type. A flexible connection herein shown in the form of a portable is connected to the terminals of the element 20' and is adapted in the usual way as by a plug 22 for detachable connection to an electric socket. 80 85

35 The bottom plate 6 is disposed within the lower portion of base *a* and secured against displacement in any preferred manner as, for instance, like that shown. 7 is a standard extending vertically upward from the central portion of bottom plate 6 and through an opening in the contracted upper end portion 8 of base *a*. A screw or other fastening means 9 extending through bottom plate 6 is screwed into the lower end of standard 7 to secure the same in position as shown. 10 is a reduced vertical extension of standard 7 which is screwed upon the reduced upper end portion 11 of the standard and at its upper free end portion is provided with a shoulder 12 which forms a support for an outwardly flared skirt or deflector 13, the lower end of which is in spaced relation to the upper end of base *a* so as to provide an air passage as indicated by the arrows. The skirt or flange 13 is of metal and of any fanciful shape and its upper end portion is by preference contracted and provided with a plurality of laterally disposed outlet openings 14. 15 is

no further material is present to vaporize the same will be indicated by the absence of vapor issuing from the end of stem 23' or around the edge of the bowl.

5 With the foregoing construction it has been found that the ordinary tobacco pipe may be readily and effectively cleaned without impairment. Particles of unburned tobacco which have been trapped by the carbon 10 secretion on the inner face of the bowl are burned and reduced to ash and, in fact, any other solid particles adhering to the interior of the bowl or bore of the stem are likewise reduced by the action of the heat from 15 the device. It will be noted that the presence of bracket 17 supports the bowl so that the inner face thereof does not come in contact with the heated portion of the deflector 20 or skirt 13 so that there is no liability on the part of the device to burn or scorch and thereby damage the bowl of the pipe.

Although I have shown and described one embodiment of my invention, I wish to have it understood that the same is susceptible of various changes; and I reserve the right to employ such as may come within the scope of the appended claims.

I claim:

1. A tobacco pipe cleaner comprising a hollow upright support having one end portion thereof provided with means adapted for insertion into the bowl of a pipe and further 30 disposed in the said body portion an electrically operated heating element.

further adapted to engage the interior of the bowl at a plurality of spaced points and thereby provide a clearance between the said end portion of the support and the inner face of the bowl, and an electrically operated heating element disposed in the said hollow support.

2. A tobacco pipe cleaner comprising a hollow upright support having one end portion thereof perforated and provided with means adapted for insertion into the bowl of a pipe and further adapted to engage the interior of the bowl at a plurality of spaced points and thereby provide a clearance between the said perforated end portion of the support and the inner face of the bowl, and an electrically operated heating element disposed in the said hollow support.

3. A tobacco pipe cleaner comprising a hollow upright support having one end portion thereof perforated a plurality of re-
